UNITED STATES PATENT OFFICE.

JESSE C. COOK, OF DUQUOIN, ILLINOIS.

VALVE-SPRING COMPRESSOR.

Application filed October 16, 1923. Serial No. 668,895.

To all whom it may concern:

Be it known that I, JESSE C. COOK, a citizen of the United States, residing at Duquoin, in the county of Perry and State of Illinois, have invented certain new and useful Improvements in a Valve-Spring Compressor; and I do hereby declare the following to be a full, clear, and exact description of the invention, such as will enable others skilled in the art to which it appertains to make and use the same.

The object of the present invention is the provision of a tool whereby to facilitate the removal and the replacement of springs in cooperative relation with the valves of internal combustion engines and which springs are normally under tension and to receive the stems of the valves with which they cooperate.

A further object of the invention is the provision of a tool which when applied is adapted to hold the springs in compressed position so that both hands may be utilized for removing or replacing the keys or other locking device applied to the valve stem to retain the springs abutment in position.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,—

Figure 1 is an elevational view of a valve spring compressor embodying the invention showing the same applied, parts being broken away and parts in section,

Figure 2 is a detail sectional view on the line 2—2 of Figure 1,

Figure 3 is a sectional detail view on the line 3—3 of Figure 1,

Figure 4 is a detail sectional view on the line 4—4 of Figure 3, and

Figure 5 is a top plan view of the preferred form of fork.

Corresponding and like parts are referred to in the following description and designated in the several views of the drawings by like reference characters.

The tool includes a sectional and an ad-

justable frame which comprises similar upper and lower members 1 and 2 and upper and lower lateral members 3 and 4. The members 1 and 2 are preferably of L-form and have a telescopic connection and are adapted to be held in the required adjusted position by means of a spring actuated catch 5 carried by the member 1 and adapted to engage one of a plurality of openings 6 of the member 2. The outer end of the member 4 is provided with a fork 7 which receives a stem 8 of the valve 9. The fork 7 may be of any preferred construction according to the nature of the valve abutment 10 and the retainer 11. The outer end of the member 2 is provided with a downwardly keeper 12 in which the member 4 is adjustably mounted and held in the adjusted position by means of a spring actuated ball catch 13 or equivalent means. As shown in Figure 2, the member 4 and the passage through the keeper 12 are of angular formation in cross section and said member has a snug sliding fit in the keeper. Due thereto, these parts are positively held against any relative angular movements during the use of the tool.

The member 3 is provided at its outer end with a guide 14 which consists of a sleeve and is laterally adjustable and adapted to be secured in the required adjusted position by means of a catch 15 similar to the catch 5. A plunger 16 is slidably mounted in the guide 14 and its lower end is pointed and adapted to engage the center openings generally provided in valves of the type shown and used in internal combustion engines. A spring actuated catch 17 mounted upon the guide 14 is adapted to engage a socket in the plunger 16 and hold the tool when the valve spring 18 is compressed so that both hands may be utilized to manipulate the locking device 11 either when removing or replacing it. A pin 19 cooperating with the catch 17 may hold the latter clear of the plunger 16 whereby the latter may be freely operated in the event of the locking device 11 being readily operable by one hand, the other hand being engaged in the manipulation of the tool. The catch 17 is slidably mounted in a boss 20 projecting outwardly from the guide 14. The outer end of said boss having an elongated opening for the pin 19 to pass through when it is required to hold the catch 17 clear of the plunger 16. The pin 19 when

withdrawn being turned to engage the outer end of the boss and hold the catch 17 in outward position.

An operating lever 21 is forked at one end and pivoted by means of the fork to the plunger 16 as indicated at 22. The link 23 is forked at opposite ends and pivotally connects the lever 21 with the guide 14 of the frame and when the outer end of the lever 10 is pressed toward the frame the plunger 16 is withdrawn and when the outer end of the lever 21 is moved away from the frame the plunger 16 is moved inwardly. When the tool is in position the pointed end of the plunger engages the valve 9 and the forked end of the member 4 engages the abutment 10 of the spring 18. With the parts in the position stated and shown in Figure 1, the swinging of the lever 21 outwardly with respect to the frame will compress the spring 18 so that the locking device 11 may be removed after which the tool is disengaged from the valve and valve spring whereby the valve may be ground or replaced as required.

It will thus be understood that the valve spring 18 may be compressed to admit of ready removal or replacement of the locking device 11 and in the event of both hands being required to manipulate the element 11 the tool may be held in operative position with the spring 18 compressed by means of the catch 17 but when the locking device 11 is of a nature to be readily manipulated by one hand the catch 17 is held in withdrawn position in the manner stated so that the tool may be operated by one hand and the other hand utilized for manipulating the locking device 11.

The preferred form of member for engaging the valve spring abutment 10 is flanged along its outer edge to engage the abutment 10 and prevent lateral movement thereof and

the opening between the fork members is such as to provide clearance for the retainer 11 in any position it may happen to occupy 45 when the tool is applied.

Having thus described the invention, what I claim is:

1. A valve spring compressing tool comprising a frame having an upper lateral member provided at its outer end with a tubular guide and a lower lateral member provided at its outer end with a downwardly extending keeper the passage of which is angular in cross section, a member of angular formation in cross section having a snug sliding fit in the keeper and provided at its outer end with a fork, a spring catch carried by the member within the keeper and cooperating therewith to secure the member against accidental sliding movement with respect to the keeper, a plunger slidably mounted in the guide, and plunger operating means.

2. A valve spring compressing tool comprising a frame having an upper lateral member provided at its outer end with a tubular guide and a lower lateral member provided at its outer end with a fork, a plunger slidably mounted in the guide and provided with a socket, a lever pivoted at one end to the plunger, a link pivoted at one end to the guide and at its other end to the lever intermediate the ends of the latter, and a spring actuated catch mounted upon and projecting from the outer side of the guide 75 and adapted to engage in the socket in the plunger.

In testimony whereof I affix my signature in presence of two witnesses.

JESSE C. COOK.

Witnesses:

WILLIS E. BROWNING,
CLARENCE COOK.
